(57) CLAIM

The ornamental design for a stand for video screen, as shown and described.

DESCRIPTION

FIG. 1 is a front top right side perspective view of a stand for a video screen, showing my new design

FIG. 2 is a rear, top, left side perspective view thereof;
FIG. 3 is a front view thereof;
FIG. 4 is a side view thereof, the opposite side being a mirror image;
FIG. 5 is top view thereof;
FIG. 6 is a bottom view thereof;
FIG. 7 is a front top right side perspective view of a modified embodiment of the design shown in FIGS. 1-6, the top and bottom views being the same as in the first embodiment;
FIG. 8 is a side view thereof, the opposite side being a mirror image;
FIG. 9 is a front view thereof;
FIG. 10 is a rear, top, left side perspective view thereof;
FIG. 11 is a front top right side perspective view of a second modified embodiment of the design shown in FIGS. 1-6, the top and bottom views being the same as in the first embodiment;
FIG. 12 is a side view thereof, the opposite side being a mirror image;
FIG. 13 is a front view thereof;
FIG. 14 is a rear, top, left side perspective view thereof;
FIG. 15 is a front top right side perspective view of a third modified embodiment of the design shown in FIGS. 1-6, the top and bottom views being the same as in the first embodiment;
FIG. 16 is a side view thereof, the opposite side being a mirror image;
FIG. 17 is a front view thereof;
FIG. 18 is a rear, top, left side perspective view thereof;
FIG. 19 is a front top right side perspective view of a fourth modified embodiment of the design shown in FIGS. 1-6, the top and bottom views being the same as in the first embodiment;
FIG. 20 is a side view thereof, the opposite side being a mirror image;
FIG. 21 is a front view thereof;
FIG. 22 is a rear, top, left side perspective view thereof;
FIG. 23 is a front top right side perspective view of a modified embodiment of the design shown in FIGS. 1-6, the top and bottom views being the same as in the first embodiment;
FIG. 24 is a side view thereof, the opposite side being a mirror image;
FIG. 25 is a front view thereof; and,
FIG. 26 is a rear, top, left side perspective view thereof.
